EXTENSIBLE HOIST

Joe D. Sumner, 6903 Alderney, Houston, Tex. 77055
Filed Aug. 13, 1965, Ser. No. 479,536
1 Claim. (Cl. 254—143)

This invention relates to hoisting mechanism and more particularly to hoisting apparatus embodying telescoping extension means for adjusting the height of the load which is supported.

The invention has for an important object the provision of hoisting mechanism which is easily moved about for use at any desired location and by which the load which is lifted may be readily moved from place to place.

Another object of the invention is to provide hoisting mechanism which is supported to be rolled about and embodying means for stabilizing the structure against overturning.

A further object of the invention is the provision in hoisting mechanism of a telescoping, extensible, upright standard or mast supported on a base having wheels disposed in radially spaced relation to the axis of the standard or mast, and means for supporting a load on the standard at a substantially centralized location relative to the wheels to increase the stability of the mechanism.

Another object of the invention is the provision in extensible hoisting mechanism of an upright mast or standard which is formed of a number of telescopingly arranged, tubular members having roller means positioned to hold the members in axial alignment during relative longitudinal movement of the members and means for imparting such relative longitudinal movement to the members to extend the same.

A further object of the invention is the provision in hoisting mechanism of the type having an upright standard or mast formed of telescopingly arranged tubular members, of cable mechanism for simultaneously extending inner ones of said members relative to each other and relative to the outermost member thereof to increase the height of the standard.

A still further object of the invention is to provide hoisting mechanism which is of simple design and rugged construction and which may be economically manufactured.

The above and other obvious objects and advantages of the invention will be apparent from the following detailed description of a preferred embodiment of the mechanism when considered in conjunction with the annexed drawings, wherein:

FIGURE 1 is a side elevational view, partly broken away and partly in cross-section, illustrating the hoisting mechanism of the invention and showing the same in a substantially fully retracted position;

FIGURE 2 is a cross-sectional view, taken along the line 2—2 of FIGURE 1, looking in the direction indicated by the arrows;

FIGURE 3 is a cross-sectional view taken along the line 3—3 of FIGURE 1, looking in the direction indicated by the arrows;

FIGURE 4 is a fragmentary, perspective view of the cable mechanism by which the telescoping members of the upright standard or mast of the mechanism are operated, showing the cable mechanism removed from the surrounding structure of the hoisting mechanism and with the parts in the positions which they occupy when the telescoping members are retracted;

FIGURE 5 is a view similar to that of FIGURE 4, showing the parts of the cable mechanism in the positions which they occupy when the telescoping members are extended, illustrating the manner in which the height of the standard or mast is increased;

2

FIGURE 6 is a cross-sectional view on an enlarged scale taken along the line 6—6 of FIGURE 1, looking in the direction indicated by the arrows;

5 FIGURE 7 is a cross-sectional view on an enlarged scale, taken along the line 7—7 of FIGURE 1, looking in the direction indicated by the arrows;

FIGURE 8 is a cross-sectional view on an enlarged scale, taken along the line 8—8 of FIGURE 1, looking in the direction of the arrows;

10 FIGURE 9 is a cross-sectional view on an enlarged scale, taken along the line 9—9 of FIGURE 1, looking in the direction indicated by the arrows; and

15 FIGURE 10 is a cross-sectional view on an enlarged scale, taken along the line 10—10, looking in the direction indicated by the arrows.

20 Referring now to the drawings in greater detail the hoisting mechanism of the invention includes a base or supporting frame made up of elongated frame members 10, 10 and 12, 12 whose inner ends are secured to a connector plate 14, or the like, the members diverging outwardly from the plate in the same horizontal plane and having their outer ends positioned in a substantially rectangular arrangement. The members may be secured to the plate 14 by any suitable means, such as welding and each member is supported at its outer end by a wheel or caster 16 mounted for swivelling movement about a vertical axis to allow the structure to be easily rolled about in any direction.

25 The hoisting mechanism includes an extensible upright standard or mast, generally designated 18, formed of telescopingly arranged, elongated, tubular elements of generally rectangular shape in cross-section, the outermost one, 20, of which extends through the plate 14 and is attached thereto near its lower end. The lower end of the element 20 is connected to the member 10, 10 and 12, 12 by braces 22 and 24, as shown in FIGURE 1, as by means of welding or the like. The mast 18 is thus held rigidly upright at a location somewhat offset to one side of the center of the base.

30 The mast or standard 18 has an intermediate tubular element 26 which telescopes within the element 20, and an inner element 28 which is telescopingly disposed in the element 26. Thus, the outermost element 20 is stationary on the base while the intermediate element 26 and inner element 28 may be extended upwardly relative thereto and the inner element 28 may be extended upwardly relative to the element 26.

35 At its upper end, the inner element 28 carries a cross arm 30 upon whose opposite ends pulleys 32 and 34 are rotatably mounted for rotation on horizontally disposed axes. The pulley 32 is thus supported substantially vertically above the center of the supporting base.

40 Suitable cable winding mechanism is mounted on the outer element 20, which may be of the type having two winding drums or reels 36 and 38, provided with handles, as shown at 40 and 42, and which also have suitable ratchet or detent mechanisms, designated 44 and 46, respectively, of a usual type to permit the reels to be wound in one direction while preventing unreeling movement of the same. The detent mechanisms are constructed to be released when desired to allow unreeling of the winding mechanisms.

45 The reel 36 has a cable 48 wound thereon which extends upwardly, over the pulleys 32 and 34 and downwardly centrally above the base, and is provided at its free end with a load supporting hook 50, of the usual kind, and a weight 52 to assure the lowering of the hook when the reel 36 is released for unwinding. Thus by connecting the hook 50 to a load to be lifted, the cable 50 48 may be wound up to lift the load and support the same in a substantially centralized position relative to the base.

The tubular elements 20, 26 and 28 are shaped as shown, the outer element 26 being somewhat wider and longer in cross-section than the intermediate element 26, which in turn is somewhat wider and longer in cross-section than the inner element 28, whereby the elements may be telescopingly arranged, and space is provided between the elements for the cable mechanism by which the elements are extended and retracted.

For the purpose of extending and retracting the intermediate and inner elements of the mast or standard, the intermediate element 26 has a pulley 54 rotatably mounted thereon near its lower end inside of the outer element 20, and the outer element has an external pulley 56 mounted on a horizontal shaft 58, rotatably carried on brackets 60 attached to the upper end of the outer element. A cable 62 extends about the pulleys 54 and 56 and is anchored at one end to a cylindrical extension 64 of the pulley 56, surrounding the shaft 58, which cable is wound on the reel 38, so that upon winding up of the cable 62 the intermediate element 26 will be extended upwardly and upon unwinding of the cable the intermediate element will move downwardly in the outer element.

A pulley 66 is rotatably mounted on the inside of the intermediate element 26, inner element 28, near its lower end, and the intermediate element 26 has a pair of pulleys 68, 68 rotatably mounted on brackets 69, 69 on the upper end of the intermediate member, and a cable 70 passes about the pulley 66 and over the pulleys 68, 68, as shown in FIGURES 4 and 5, and is attached to the cylindrical extension 64 by eyes or loops 72, so that upon extension of the intermediate element 26 by the winding up of cable 62, cable 70 will be operated to extend inner element 28 simultaneously with the intermediate element.

For the purpose of holding the tubular elements in longitudinal alignment, as shown, to maintain the elements in properly spaced relation to accommodate the pulleys 54 and 66 between the elements and provide space for the cables 62 and 72, the outer element has a roller 74 rotatably mounted between the brackets 60, 60 as shown in FIGURE 7 which bears against an outer face of the intermediate element 26, and the intermediate element has a roller 76 rotatably mounted thereon adjacent its lower end which bears against an inner face of the outer element to hold these elements in longitudinal alignment in all relative longitudinal positions of the elements. Similarly, the inner element 28 carries at its lower end an externally mounted roller 78 positioned for engagement with an inner face of the intermediate element 26, and the intermediate element also carries a roller 80, shown in FIGURE 6, rotatably mounted on the brackets 69, 69, in position for engagement with an outer face of the inner element, to hold the intermediate and inner elements in the same position of longitudinal alignment in all relative longitudinal positions of the intermediate and inner elements. By this arrangement the elements are prevented from tilting relative to each other when extended, thus avoiding any tendency of the elements to bind against each other.

The intermediate element 26 may also be provided with external guiding or spacing members 82, 82 at its lower end extending along opposite sides of the element in position for sliding engagement with opposite, internal, side surfaces of the outer element 20 to hold the intermediate element centralized laterally therein.

In making use of the hoisting equipment, constructed as described above, the base frame may be rolled up to and object to be lifted and the cable 48 unwound to allow the hook 50 to be hooked to the load, whereupon the cable may be wound up to lift the load and suspend the same in a position substantially centered above the frame.

With the load thus suspended, the hoist may be rolled to any desired location. Because of the centering of the load with respect to the wheels 16, the stability of the

device is greatly enhanced, so that there is little or no danger of overturning the equipment.

When it is desired to elevate the load, this may be accomplished by winding up the cable 62 which extends the intermediate element 26, whereby the cable 70 and pulleys 68, 68 are actuated to extend the inner element 28. During extension of the mast the inner element 28 will be extended relative to the intermediate element as the intermediate element is extended relative to the outer element, thus providing an arrangement which is very steady and stable in operation and which may be very easily and quickly adjusted to any desired height. Due to the cable and pulley arrangement by which the mast is extended, the close fitting of the inner element 28 laterally in the intermediate element, and the roller guiding and spacing means provided for the elements, relatively heavy loads may be rapidly elevated without wobbling or loose play.

The invention thus provides extensible hoisting mechanism which is of simple design, strong and rigid construction and which is easy to operate.

The invention is disclosed herein in connection with a particular embodiment of the same, which is intended by way of illustration only, and it will be apparent that various modifications can be made within the spirit of the invention and the scope of the appended claim.

Having thus clearly shown and described the invention, what is claimed as new and desired to secure by Letters Patent is:

30 Hoisting apparatus comprising a supporting frame, an outer, elongated, tubular element fixedly attached at its lower end to the frame and extending upwardly therefrom, an intermediate, elongated, tubular element in and movable longitudinally in the outer element, an inner, elongated, tubular element in and movable longitudinally in said intermediate element, all of said elements being of generally rectangular shape in cross-section, an upper, elongated roller rotatably carried on the outer element adjacent the upper end thereof in rolling engagement with one side face of said intermediate element, a lower elongated roller rotatably carried on said intermediate element adjacent its lower end in rolling engagement with the side face of said outer element remote from said one side face of said intermediate element, an upper, elongated roller rotatably carried on the intermediate element adjacent its upper end in rolling engagement with one side face of said inner element, a lower, elongated roller rotatably carried on said inner element adjacent its lower end in rolling engagement with a side face of said intermediate element, said rollers being positioned for coaction with the elements to hold said intermediate and inner elements against tilting movement relative to said outer element, means positioned for coaction with the elements to move said intermediate elements longitudinally relative to said outer element and to each other to vary the height of the standard and means on said inner element positioned for engagement with a load to support the load in an elevated position.
